UNITED STATES PATENT OFFICE

126,597

DESIGN FOR A COMPOSITE CROSS

Raymond F. Brennan, Attleboro, Mass.

Application August 15, 1940, Serial No. 94,437

Term of patent 14 years

To all whom it may concern:

Be it known that I, Raymond F. Brennan, a citizen of the United States, residing at Attleboro, in the county of Bristol and State of Massachusetts, have invented a new, original, and ornamental Design for Composite Cross, of which the following is a specification, reference being had to the accompanying drawing, forming part thereof.

Fig. 1 is a front elevational view of the composite cross, showing my new design,

Fig. 2 is a transverse sectional view, taken on the line 2—2 of Fig. 1, and,

Fig. 3 is a sectional view taken along the lines 3—3 of Fig. 1 and showing the cross elements slightly separated from each other.

I claim:

The ornamental design for a composite cross, substantially as shown.

RAYMOND F. BRENNAN.
